UNITED STATES PATENT OFFICE.

ELOF H. MEDEN, OF ELIZABETH, NEW JERSEY, ASSIGNOR, BY MESNE ASSIGNMENTS, TO A. G. A. RAILWAY LIGHT & SIGNAL CO., INC., OF ELIZABETH, NEW JERSEY, A CORPORATION OF NEW JERSEY.

RAILWAY SIGNALING APPARATUS.

Application filed July 13, 1918. Serial No. 244,683.

To all whom it may concern:

Be it known that I, ELOF H. MEDEN, a subject of the King of Sweden, residing in the city of Elizabeth, county of Union, 5 State of New Jersey, have invented certain new and useful Improvements in Railway Signaling Apparatus, of which the following is a specification.

In order that a railway signaling apparatus should be entirely satisfactory, it is necessary that it should comprise means whereby the greatest degree of safety is provided and it is also desirable and necessary that the apparatus should operate with both 15 certainty and efficiency.

Broadly speaking, it is the object of my invention to provide an apparatus having these characteristics, the results sought being accomplished by providing means whereby normally a danger signal is displayed, which is changed only when the track ahead is clear for an approaching train or when caution should be observed by the engineer of an approaching train. In the latter case, 20 a caution signal and in the former a clear signal is displayed.

A further object of my invention is to provide means for producing a plurality of colored lights, one light only being displayed at a time, automatically, the light 25 displayed being dependent upon track conditions.

A further object of my invention is to provide a railway signal lighting apparatus or 30 system comprising at intervals therein renewable sources of illuminating gas supply for supplying gas to the signal light burners.

Other objects and advantages of my invention will be pointed out in the detailed 35 description thereof which follows or will be apparent from such description.

It will be understood that my invention is not limited to the details of construction shown, but is capable of embodiment in wide 40 variations and modifications of structure.

In order that my invention may be more readily understood and its practical advantages more fully appreciated, reference should be had to the accompanying drawings, in which,—

Fig. 1 is a view showing diagrammatically a portion of railway track, track circuits and signaling means actuated and controlled

thereby, constructed in accordance with my invention;

Fig. 2 is a view partly in vertical section and partly in side elevation, showing in detail a construction of signal light apparatus embodying my invention;

Fig. 3 is a view similar to that shown in Fig. 2, showing a modified construction of apparatus embodying my invention;

Fig. 4 is a vertical sectional view of an electromagnet construction interposed in the gas supply conduit;

In the drawings:—1 designates a railway track over which pass railway trains, etc., indicated symbolically at 2, 2^a and 2^b. 3 designates the batteries of track circuits, including sections of the rails and the wires 4 and 5, each of the said circuits including electro-magnets 6. The sections of the rails referred to are included between the transverse heavy lines 7. These electro-magnets actuate and control armatures 10, 11 and 12, 75 there being one set of armatures and one track circuit and an electro-magnet for each section of railway track intermediate the said heavy lines 7. These armatures, 10, 11 and 12, constitute and form parts of the 80 signal control circuits which extend through signal controlling electro-magnets 15 and 16, the energizing and de-energizing of which control the signal lights, said lights being indicated diagrammatically at 17, 17^a, 17^b, 17^c, and 17^d in Fig. 1. The solid cross-lines 17^a at the left hand side of Fig. 1 indicate that the caution signal light is operating, while the solid cross-lines 17^b in the second, 85 fourth and fifth group of signal lights indicate that the danger signal light is in operation, while the solid cross-lines 17^c in the central group of signal lights, indicate that the track ahead for the car or train 2^a is clear. The solid cross-lines 17^d indicate that in view of the presence of the car or train 2^a in the second section beyond that in which the car or train 2 is located, the engineer of 90 the latter should move with caution.

20 designates storage batteries, there being shown one battery for each of the sections of track above referred to intermediate the heavy black lines 7. These batteries furnish the current for the circuits including the electro-magnets 15 and 16 above referred to, and it is the passage of current 100 105

2
through these circuits that controls these magnets, the controlling of which also controls the light signals which are produced, as will more fully and clearly appear from 5 the detailed description of Figs. 2, 3 and 4 of the drawings which follows.

Tracing the current through the circuits controlling the signal 17^b, it will be found to travel through the line 21, the armature 10, line 22, ground line 23, line 24, armature 11 (at the right hand side of Fig. 1), line 25, armature 12 (in the fourth group of armatures from the left in Fig. 1), line 26, through the electro-magnet 16 and line 27 to battery 20.

It will also be noted that the circuit passes through the line 21, armature 10, line 22, ground line 23, line 28, armature 11 (in the fourth group of armatures counting from the left in Fig. 1), line 29, electro-magnet 15 and line 27 to the battery 20.

It will thus be seen that when the signal is shown in clear position as at 17^c in the central group of signal lights, both of the 25 electro-magnets 15 and 16 are energized. When the caution signal is shown as at 17^e in Fig. 1, only the electro-magnet 15 is energized. This may be seen or demonstrated by tracing the circuit from the battery 20, shown at the left hand side of 30 Fig. 1.

Normally, that is when there are no trains, engines or cars upon the track and also when there is danger ahead upon the 35 track the danger signal is displayed. At such time neither of the electro-magnets 15 or 16 is energized in consequence of which, as will be hereinafter fully set forth, gas is permitted to flow continuously or at 40 intervals as may be preferred to the burner for the danger signal light. When electro-magnet 15 is energized the flow of gas to the burner for displaying the "danger" signal is interrupted, so that such signal 45 is no longer displayed and simultaneously flow of gas to the next burner is permitted, which upon ignition causes a display of the "caution" signal. When both 50 electro-magnets 15 and 16 are energized, the flow of gas to the burner for displaying the "danger" signal and also to the burner for displaying the "caution" signal is interrupted, but is permitted to flow to the 55 burner for displaying the "clear" signal, so that in the event of energization of both electro-magnets 15 and 16 the "clear" signal is displayed. In other words, normally the signal indicates danger and it is only when a train, engine or the like is 60 approaching and when the track ahead is clear that the signal device moves into the clear position indicating that the train may proceed rapidly and without caution. In case, however, there should be two trains 65 in positions such as the trains 2 and 2^a in

Fig. 1, said trains being separated by an intervening section such as is indicated between the lines 7, 7 previously referred to, the caution signal light is caused to be displayed. On the other hand, should there be a train such as that indicated by the dotted lines at 31 in Fig. 1 in the section of track adjacent to that on which the train at 2 is located, the danger signal would continue to be displayed; that is, the signal apparatus would continue to display a red light, as indicated by the dotted cross-lines at 31^a in Fig. 1. This can be seen readily by tracing the circuit from the battery 20 at the left hand side of Fig. 1 and assuming that a train, engine, etc. is in a position indicated by dotted lines 31 in Fig. 1, in which case the track circuit will be short circuited so that the electro-magnet 6 would be de-energized, permitting the 85 armatures 10, 11 and 12 in the second group of armatures counting from the left of Fig. 1 to drop or fall so as to permit the armature 10 to fall or move into position against contact 32, while at the same time 90 permitting the armatures 11 and 12 to fall or move away from the contacts 33 and 34.

The circuits and their general operation having been described, I shall now proceed with a description of the subsequent 95 Figs. of the drawings, in which I have illustrated a concrete embodiment of apparatus constructed in accordance with my invention.

For the purpose of supporting the signal 100 lights, casings for the same, portions of the signal light controlling means, etc., I have provided posts 40 which are situated at intervals along the track.

It is my purpose to employ gas lights in 105 producing the light signal. This being the case, it is necessary to provide a source or sources of gas supply. In the construction as illustrated and as at present preferred by me, I provide renewable sources of gas supply 110 comprising containers 41, containing gas under compression, which gas may be supplied as necessary and as required to the signal light burners to be hereinafter referred to more in detail. Preferably one 115 container is provided for each group of signal light burners and each container is adapted to carry a supply of gas sufficient to produce operation of the signal for extended periods. One of the containers 41 is 120 shown in Fig. 2 of the drawings and is held removable in position as indicated in said Fig. by removable or detachable straps 41^a. The said container is detachably connected at 41^b with a conduit 42 through which gas 125 is supplied to the burners. 43 designates a pressure gauge for indicating the pressure of gas within the tank 41 and 44 designates a pressure regulating device for regulating the 130 pressure of gas which is supplied to the sig-

nal light burners. Interposed in the conduit 42 intermediate the supply tank 41 and the burners 45, 46 and 47 are electro-magnetically controlled valve constructions respectively indicated as a whole by the reference number 48, for controlling and regulating or directing the flow of gas to the burners. The condition of the electro-magnets is dependent upon the track conditions, so that the burners 45, 46 and 47 will be lighted in accordance with and independently upon the track conditions. In the construction shown, there are two of these electro-magnetically controlled valve constructions, associated with each group of signal lights.

The gas is admitted first to the lowermost of the said electro-magnetically controlled valve devices 48 from the pipe or gas conduit 42. The latter communicates with a passage 50, formed in what may be termed or described as the base portion 51 of the said device 48. The passage 50 communicates with passageways 52 and 53, the former leading to the second of the devices 48.

25 The base portion 51 of the devices 48 (the several devices 48 shown in Figs. 2 and 3 being identical in construction) is provided with a depression 54 at its inner central portion in which is situated an electro-magnetically controlled valve 55, which operates to close either the passageway 52 or 53 depending upon the condition of the electro-magnet 58, by means of which the said valve 55 is controlled. Normally the valve 55 occupies a position to close the passageway 52. When in this position the passageway 50 is in communication with the passageway 53 through the core 60, the latter passageway being in communication with a pipe 61, through which gas is supplied to burner 45. Said burner is situated in the rear of a red colored lens 62. The burner 45 is active at all times except when the electro-magnet 58 is energized. However, it will be understood 45 that preferably a flasher device, such as is shown at 63 in Fig. 3 of the drawings, may be employed in order to render the operation of the apparatus more economical. Further reference will be made to this flasher device 50 later on in this specification.

It will be understood that the electro-magnets 48 shown in detail in Figs. 2, 3 and 4 of the drawings correspond with the electro-magnets 15 and 16 comprised in the diagrammatically illustrated apparatus as shown in Fig. 1.

In case the trains, engines, etc. should be in positions as indicated by the reference numbers 2 and 2^a in Fig. 1 of the drawings, 60 it is apparent that the caution signal should be displayed. When the trains are in this position, and as has been described previously, the lower of the two electro-magnets (corresponding to the electro-magnet 15 in Fig. 1) becomes energized, with the result

that the valve 55 is lifted from the position in which it is shown in Fig. 4 into position to close the passageway 53 and simultaneously open the passageway 52, thus putting the passageway 50 into communication 70 with the latter. The gas may then pass through the passageways 50 and 52 to the pipe 64, which is in communication with the upper one of the devices 48, shown in Figs. 2 and 3, the construction of which is in all respects the same as is illustrated in Fig. 4 of the drawings, so that the gas which passes from the pipe 64 into the upper of said devices is conducted through passageways 50 and 53 to a pipe 65, leading to the burner 80 46, which is situated in the rear of the yellow colored condensing lens 66. It will be seen that the flame or light of burner 45 has been extinguished and that the burner 46 has been lit or ignited.

Should it be that the track in front of the train indicated at 2 is clear, the electro-magnet in each of the devices 48, shown in Figs. 2 and 3, would be energized, as previously pointed out, with the result that the valve 55 90 in the uppermost as well as in the lowermost of said devices shown in both Figs. 2 and 3, would be moved into position to close the passageway 53, thus preventing the passage of gas into the pipe 65. Such movement, 95 as already described, would put the passageway 50 in communication with the passageway 52, so that the gas would pass through the upper of the devices 48 into the pipe 67 leading to the uppermost burner 47 100 situated in the rear of the uppermost green colored condensing lens 68.

Constantly burning or lighted pilot burners 69 are provided for igniting the gas as it issues from the burners 45, 46 and 47. 105 The pilot burners 69 are supplied with gas from a pipe 70 having connection in Fig. 2 at 71 with the lowermost of the devices 48 therein.

In Fig. 3, the pipe 70 instead of being 110 connected with the lowermost of the devices 48 is connected with the gas pipe or conduit 42 at a point preceding the connection of the latter with the flasher device 63, the latter being of any known construction. 115

From the flasher device the gas is supplied at intervals through the pipe 75 to the lowermost of the devices 48. The flasher device 63 is not illustrated in further detail because such devices, as above indicated, are 120 old and are at present in quite general commercial use.

In Fig. 2, as previously described, the gas pipe or conduit 42 is connected directly with the lowermost of the devices 48, while as 125 shown in Fig. 3 the said conduit is first connected with the flasher device 63.

In both Figs. 2 and 3, I have shown what may be described or defined as a hood 80, which surrounds the lenses 62, 66 and 68, 130

its purpose being to throw or cast a shadow from the said lenses to the surface of the frames surrounding and supporting them in order to darken the same so that they may be more readily and clearly distinguishable in daylight. In the brighter portions of the day, that is, the portions nearer noontime when the sun is nearer to or in a vertical position in the heavens, the rays therefrom will strike the hood 80 and the latter will cast a shadow over the face of the lenses and the frames surrounding the same, as stated.

In view of the forms of construction shown in Figs. 2 and 3, I have provided a casing 81 for inclosing the operative parts of the structure as illustrated in said Figs.

The lower portion of the casing in Fig. 3 is somewhat enlarged in order to enable it to receive and hold the flasher device 63 in addition to the parts which are contained in the casing shown in Fig. 2.

In both Figs. 2 and 3 of the drawings, the lowermost devices 48 are supported upon the bottoms of the casings 81, while the upper of said devices are supported upon projecting flange-like portions 82 which extend inwardly from a side wall thereof as is clearly shown. Obviously, however, these devices 48 may be supported at any convenient point and in any suitable manner within the casings or in operative relation to the burners.

This application is a continuation in part of my applications for patents filed January 4, 1917 and February 15, 1918 respectively and bearing Serial Nos. 140,554 and 217,299 respectively.

I claim:

In a railway light signaling apparatus and in combination, a signaling lantern having a plurality of main gas burners and pilots, a renewable source of compressed illuminating gas, a gas conduit leading from said source to said gas burners, electro-magnetically controlled valves in said conduit for controlling the flow of gas to the burners and normally being in position to permit the flow of gas to one of said burners to display a "danger" signal, controllable circuits within which the valve magnets are included, said circuits being unaffected by gas movements, means whereby said circuits are controlled by train movements over a track associated with said apparatus, the construction and arrangement of the parts being such that magnet activity to close the gas supply of the burner to which gas normally is being supplied will be provided upon change in conditions of the controllable circuit and to simultaneously open the gas supply to one of the other main burners.

In testimony that I claim the foregoing as my invention, I have hereunto set my hand and seal this 29th day of June, A. D. 1918.

ELOF H. MEDEN.
